UNITED STATES PATENT OFFICE

DAVID E. MACCABEE, OF DAYTON, OHIO, ASSIGNOR TO FRIGIDAIRE CORPORATION, OF DAYTON, OHIO, A CORPORATION OF DELAWARE

REFRIGERATING APPARATUS

Application filed July 31, 1928. Serial No. 296,492.

This invention relates to refrigerating apparatus and particularly to soda fountains and similar devices in which various commodities of different characters are maintained at different temperatures.

It is one of the objects of the invention to provide a simplified and economical refrigerating system particularly adapted to soda fountains.

Another object of the invention is to provide an improved and simplified arrangement for maintaining a number of different temperatures by means of a single refrigerating system.

More specifically it is one of the objects of the invention to operate a plurality of evaporating elements in series and to provide an improved and simplified means for controlling the amount of liquid refrigerant which enters successive evaporators of the series.

Further objects and advantages of the present invention will be apparent from the following description, reference being had to the accompanying drawings, wherein a preferred form of the present invention is clearly shown.

In the drawings:

Fig. 1 is a diagram of a refrigerating system embodying the present invention;

Fig. 2 is a plan view of a soda fountain having a refrigerating system constructed in accordance with the invention; and

Fig. 3 is an end elevation of the same.

It is usual to provide soda fountains with a compartment for storing ice cream which should be kept at a temperature of 70° F. or less, a compartment for storing and cooling water on draft which should be maintained at a temperature of around 40° and a compartment for containers of fountain syrups, fruit juices and the like, commonly called a syrup rail, which should be maintained at a temperature of 55° F. or less.

My invention is concerned with an improved arrangement and method for maintaining the above mentioned compartments at their individual proper temperatures by means of a single refrigerating system or apparatus.

Referring to Figs. 2 and 3 of the drawings 10 designates any suitable soda fountain which is provided with an ice cream compartment 11, a water compartment 12 and a syrup rail 13 for holding the syrup containers 14. Each of the compartments may be suitably insulated according to the temperatures at which it is to be maintained. A relatively high pressure evaporator 16 is placed in the water compartment and a relatively low pressure evaporator 17 placed in the ice cream compartment. Referring to Fig. 1, these evaporators are preferably of the flooded type and each include a header 20 forming a reservoir for liquid refrigerant which is kept at a constant level therein under the control of a float valve 22, and refrigerant circulating tubes or coils 23. The evaporators are supplied with liquid refrigerant through liquid lines 26 and 27 connected in parallel to a condensing element generally denoted by 28 which also withdraws evaporated refrigerant from both said evaporators through a vapor conduit 29.

Refrigerant evaporated in the evaporator 16 is withdrawn through a conduit 30 which is ultimately connected to the conduit 29 and which is provided with any suitable pressure regulating shut-off valve 31, the construction of which may be, for example as is illustrated and described in the application of Ernest Dickey Serial No. 753,048, filed December 1, 1924. This valve is opened by the pressure of refrigerant in the evaporator 16 and automatically closes at some predetermined low pressure corresponding, for example, to 35° F. and thus prevents refrigeration of the evaporator below that temperature.

The condensing element 28 includes any suitable compressor 32 actuated by a motor 33 under the control of a switch 34 which is operated in response to the pressure existing in the vapor conduit 29. When the pressure existing in this conduit is above that corresponding to a temperature of about 5° F. the switch closes to actuate the compressor and withdraw the refrigerant from the evaporator 17 until the pressure has been reduced to a value corresponding to a predetermined low temperature, for example zero degrees.

Refrigerant is evaporated in and withdrawn from evaporator 16 only when the pressure regulating valve 31 is open, that is, when the temperature of 16 is above 35° F.

- 5 The conduit 30 connecting the evaporator 16 and the exhaust conduit 29 includes a portion forming the condensing coil 34^a which is in thermal relation with the evaporator 17, and a portion 35 forming an evaporator 10 which is in thermal relation with the syrup rail. Preferably the evaporator 17 is immersed in a non-freezing solution such as brine as is usual in cases of this character, and the condensing conduit 34^a is also immersed in the brine.

15 Whenever refrigerant is withdrawn from the evaporator 16 under control of the pressure regulating valve 31, this refrigerant will be, for example at a temperature of 35°

- 20 F. and a pressure of about 9 pounds per square inch gauge. The refrigerant comes in contact with the brine at a temperature, for example of 7° F. This is, of course, cold enough to condense some or all of the refrigerant at this or a lower pressure. The condensed refrigerant is therefore drawn into the conduit 35 associated with the syrup rail and is there evaporated, supplying refrigeration for the syrup. The evaporated refrigerant is finally drawn into the compressor to be condensed and circulated through the system again. The temperature at which the syrup rail is maintained is regulated by the amount of refrigerant which is evaporated 25 in a unit of time in the coil 35. This is in turn controlled by the amount of liquid refrigerant which is condensed in the coil 34^a.

30 Since under certain conditions all of the refrigerant condensed in the coil 34^a may not be evaporated in the coil 35 it is desirable to provide means for preventing the remaining liquid refrigerant from being drawn into the vapor conduit 29. This is accomplished by connecting the coil 35 to the conduit 29 35 through the header 20 of the evaporator 17 as shown in Fig. 1. The header thus forms a trap which collects any liquid refrigerant discharged from the conduit 35 and permits only gaseous refrigerant to be drawn into the conduit 29.

40 The above described system provides a very simple and reliable method of cooling the syrup rail of a soda fountain and of controlling the amount of liquid refrigerant 45 which is admitted to the syrup rail evaporator.

45 While the form of embodiment of the invention as herein disclosed, constitutes a preferred form, it is to be understood that other forms might be adopted, all coming within the scope of the claims which follow.

50 What is claimed is as follows:

- 55 1. Refrigerating apparatus comprising in combination a refrigerant circulating device, a pair of refrigerating elements connected in

series between the outlet and inlet of the circulating device, and means between the elements for cooling refrigerant issuing from the first element.

60 2. Refrigerating apparatus comprising in combination a condensing element, a pair of evaporators connected in series between the outlet and inlet of the condensing element, and means between the evaporators for condensing gaseous refrigerant issuing from the first evaporator.

65 3. Refrigerating apparatus comprising in combination a pair of evaporators connected in series, means for circulating volatile refrigerant through the evaporators and means between the evaporators for condensing, at a pressure no greater than the evaporating pressure, refrigerant issuing from the first evaporator.

70 4. Refrigerating apparatus comprising in combination a condensing element, a pair of evaporators connected in series between the outlet and inlet of the condensing element, a condenser for condensing at least a portion of the gaseous refrigerant issuing from the first evaporator, and a third evaporator for evaporating refrigerant from the condenser.

75 5. The method of refrigerating which consists in circulating volatile refrigerant through a pair of evaporators in series, evaporating said refrigerant in the first evaporator, condensing some or all of said evaporated refrigerant and evaporating said condensed refrigerant in the second evaporator.

80 6. The method of refrigerating which consists in circulating volatile refrigerant through a pair of evaporators in series, evaporating said refrigerant in the first evaporator, condensing some or all of said evaporated refrigerant at a pressure no greater than the evaporating pressure and evaporating said condensed refrigerant in the second evaporator.

85 7. Refrigerating apparatus comprising in combination a pair of evaporators connected in series, a condensing element for supplying liquid refrigerant to and withdrawing gaseous refrigerant from the series, a third evaporator connected in parallel circuit relation with the series and a condensing conduit between the evaporators of the series thermally associated with the third evaporator.

90 8. The method of refrigerating which consists in circulating volatile refrigerant in a closed system including a pair of refrigerating elements connected in series, evaporating refrigerant in the first element of the series, evaporating a portion of the refrigerant in the system to condense refrigerant evaporated in the first element, and evaporating the condensed refrigerant in the second element of the series.

95 9. Refrigerating apparatus comprising in

combination a pair of evaporators, a conduit connecting the evaporators in series, and a third evaporator connected in parallel circuit relation with the series, the conduit being thermally associated with the third evaporator.

10. Refrigerating apparatus comprising in combination a pair of evaporators, a conduit connecting the evaporators in series, a container for a non-freezing liquid, and a third evaporator in the container and connected in parallel circuit relation with the series, said conduit passing through said container.

11. Refrigerating apparatus comprising in combination a relatively high temperature compartment, a relatively low temperature compartment and a compartment to be maintained at an intermediate temperature, means for refrigerating all such compartments including an evaporator in the intermediate temperature compartment and an evaporator in the low temperature compartment connected in parallel circuit relation with the first mentioned evaporator, a third evaporator in the high temperature compartment connected in series with the first mentioned evaporator, and means associated with the low temperature evaporator for condensing gaseous refrigerant passing from the intermediate temperature evaporator to the high temperature evaporator.

12. A soda fountain comprising in combination an ice cream compartment, a compartment for circulating water, a compartment for storing syrup and means for refrigerating said compartments including a refrigerant circulating device, an evaporator associated with each compartment, the water compartment evaporator and the syrup compartment evaporator being connected in series with each other and in parallel circuit relation with the ice cream compartment evaporator, and means for condensing gaseous refrigerant issuing from the water compartment evaporator before such refrigerant enters the syrup compartment evaporator.

13. Apparatus defined in claim 12 wherein the condensing means is a conduit thermally associated with the ice cream compartment evaporator.

14. A soda fountain comprising in combination an ice cream compartment including a brine tank, a compartment for circulating water, a compartment for storing syrup, and means for refrigerating said compartments including an evaporator associated with each compartment, and a conduit passing through said brine tank connecting the water compartment evaporator and the syrup compartment evaporator in series with each other, the ice cream compartment evaporator being connected in parallel circuit relation with said series.

15. The method of refrigerating which

consists in maintaining a constant supply of liquid refrigerant at low pressure in heat exchange relation with a compartment to be cooled, evaporating the refrigerant in response to the refrigerating demand of said compartment, withdrawing all of said evaporated refrigerant, condensing some or all of said evaporated refrigerant at the evaporating pressure, and evaporating said condensed refrigerant in thermal association with a second compartment to be cooled.

16. Refrigerating apparatus comprising in combination a refrigerating chamber, means for maintaining a constant supply of liquid refrigerant at low pressure in said chamber, a second refrigerating chamber, means for evaporating and withdrawing refrigerant from the first chamber in response to the refrigerating demand of said chamber and for delivering said refrigerant to the second refrigerating chamber, and means for condensing some or all of the evaporated refrigerant from the first mentioned refrigerating chamber at the evaporating pressure before said refrigerant passes to the second refrigerating chamber.

17. Refrigerating apparatus comprising in combination a pair of evaporators connected in series, a condensing element for supplying liquid refrigerant to and withdrawing gaseous refrigerant from the series, a third evaporator connected in parallel circuit relation with the series and a condensing conduit between the evaporators of the series thermally associated with the third evaporator, said apparatus including a trap for liquid refrigerant between the series and the condensing element.

In testimony whereof I hereto affix my signature.

DAVID E. MACCABEE.
